DESIGN FOR A KNITTING NEEDLE

Iris Salmon Ellis, Forest Hill Village, Ontario,
Canada

Application July 26, 1935, Serial No. 57,807

Term of patent 14 years

To all whom it may concern:

Be it known that I, Iris Salmon Ellis, a subject of the King of Great Britain, and resident of Forest Hill Village, in the Province of Ontario, in the Dominion of Canada, have invented a new, original, and ornamental Design for a Knitting Needle, of which the following is the specification, reference being had to the accompanying drawing, forming part of the same.

In the drawing, the figure is a perspective view of the knitting needle.

I claim:

The ornamental design for a knitting needle as shown.

IRIS SALMON ELLIS.
